CLUTCH AND PATTERN DRUM MECHANISM

Eugene St. Pierre, Pawtucket, R. I., assignor to
Hemphill Company, Providence County, R. I.,
a corporation of Massachusetts

Application June 23, 1945, Serial No. 601,296

10 Claims. (Cl. 66—155)

1

This invention relates to a new and useful improvement in mechanism for operating the clutch and pattern drum or drums of a knitting machine particularly of the circular independent needle type such as the well-known Banner machine.

Heretofore it has been customary to affix the clutch drum and one or more pattern drums to the same shaft. To operate the clutch it has been necessary to rotate the clutch drum the equivalent of four moves of the pattern drum. Consequently, each time clutching was performed at least three pattern drum moves were lost. A total of twelve to sixteen moves for each revolution of the pattern drum were wasted in this way. By this invention the loss of pattern drum moves through clutching is reduced to one per operation and the operation of the pattern drum is made independent of the clutch drum at all other times unless the clutch drum is also used as a pattern drum for certain special operations.

The form of the invention selected for description herein is designed for the Banner type, independent needle, knitting machine but the invention is not so limited because it may readily be adapted to other types of knitting machines.

In the drawings:

Fig. 1 is a front elevation of a part of a knitting machine illustrating the clutch drum, the pattern chain and its sprocket and a pattern drum together with their operation mechanisms and also the clutch operating mechanism;

Fig. 2 is a side elevation illustrating particularly the clutch drum, ratchet and pawl, the clutch operating mechanism and the means whereby the pawl is controlled;

Fig. 3 is a plan view of a part of the mechanisms of Fig. 1;

Fig. 4 is a view illustrating the pattern drum ratchet and pawl and the pawl operating mechanism;

Fig. 5 is a view illustrating the pattern chain ratchet, its operating mechanism, the pattern drum operating pawl and the means for controlling this pawl;

Fig. 6 is a view also illustrating the pattern drum pawl and its controlling means in another position;

Fig. 7 is a detail of the pattern chain and its relation to the pawl controlling mechanism under certain conditions;

Figs. 8 and 9 are a side elevation and plan view respectively of an auxiliary control device for the clutch drum pawl; and

2

Fig. 10 is a developed view of the clutch ratchet, drum and clutch cams.

As shown in Fig. 1 the invention includes a clutch drum 1 provided with eight clutch operating cams 2 and 3 in two sets. A clutch operating lever 4 is so pivoted as at 5 that its end 6 will follow the track provided by cams 2 and 3. Ordinarily, when the end 6 of clutch lever 4 is on a cam 2, the clutch is shifted to cause the machine to knit in a rotary manner. When the end 6 of clutch lever 4 is riding upon a cam 3 the clutch is reversed so that the machine is reciprocating.

The nature of the clutch is too well known to require detailed description. It is generally shown in Figs. 1 and 2 as consisting of a clutch member 7 and operating mechanism including a yoke 8 and a shifting rod 9 pivotally connected to the end 10 of clutch lever 4 whereby the clutch is shifted. Ordinarily, clutching occurs four times during the knitting of a stocking—at the beginning and end of the heel and at the beginning and end of the toe. Since the pattern drum shown herein provides for eight clutching operations, only one-half of one revolution of the clutch drum is required for a stocking. This makes it possible to utilize the clutch drum for other purposes such as "tipping." In such case, the cams are altered to provide four clutching operations per revolution, the reciprocatory clutching operation being extended through the normally intervening rotary period. Yarn change levers such as those indicated at 11 may then be operated by suitably positioned rows of cams (not shown) on the clutch drum to effect the necessary yarn changes.

As usual, the clutch drum is rotated by a pawl 12 (Fig. 2) mounted upon the quadrant shaft 13 and adapted to engage clutch drum ratchet 14. When in operation each working stroke of this pawl will rotate the clutch drum sufficiently to effect a full clutching operation, i. e., from rotary to reciprocatory motion or vice versa. Ordinarily, this is the equivalent of four moves of the pattern drum and, heretofore, since the pattern drum has been attached to the same shaft as the clutch drum, it has resulted in a loss of at least three pattern drum moves.

In this invention the pattern drum 15 is freely rotatable with its shaft and is turned by its own pawl 16 operating upon ratchet 17 (see Figs. 1, 3, 4, 5 and 6). Pawl 16 also is operated from the quadrant 18 by means of an adjustable link 19. Pawl 16 is capable of turning pattern drum 15 to the extent of one or two teeth of ratchet 17

per working stroke which is the equivalent of one or two moves of the pattern drum.

The machine is also provided with the usual pattern chain sprocket 20 and pattern chain 21 turned at a constant rate by means of ratchet 23 and pawl 22 which is operated from quadrant shaft 13 by suitable mechanism such as that shown in Fig. 5. Pawl 22 is so arranged that it will move the pattern drum the distance of one tooth of ratchet 23 per working stroke.

The pattern chain is adapted to carry the usual lugs by means of which it is able to control various operations of the machine. Associated with the pattern chain sprocket 20 so as to be engageable by such lugs is a rock lever 24 attached to a shaft 25 rotatably mounted in suitable bearings and having an extension projecting towards clutch drum sprocket 14 and having affixed at this end another rock lever 26.

The tail 27 of rock lever 26 is provided with a depending hook 28 (Fig. 2) which passes under the forward end of pawl 12. Whenever a pattern chain lug passes under rocker 24 it will lift that end of the rocker and, consequently, depress the other end an amount depending upon the height of the lug. If a low lug such as 29 shown in Fig. 7 passes beneath rocker 24, the tail 30 of this rocker will be depressed sufficiently to permit pattern drum pawl 16 to engage with its ratchet 17 to turn it and, consequently, the pattern drum to the extent of one tooth which is ordinarily equivalent to a single move of the pattern drum. Since rockers 24 and 26 are connected together as already described, the tail 27 of rocker 26 will be similarly depressed. Therefore, pawl 12 which operates the clutch drum ratchet 14 will be lowered but not enough to permit the pawl to engage with the ratchet. Consequently, the clutch drum remains inactive.

If a higher pattern chain lug such as that shown at 31 in Fig. 7 passes under rocker 24, the tail 30 of that rocker will be depressed sufficiently to cause pawl 16 to operate pattern drum ratchet 15 to the extent of two teeth per throw or the equivalent of two moves of the pattern drum. The equivalent lowering of tail 27 of rocker 26 permits pawl 12 to engage with and turn clutch drum ratchet 14. As already stated, the movement of pawl 12 when in operation is sufficient to rotate ratchet 14 and, consequently, clutch drum 1, a full clutching operation which is ordinarily the equivalent of four moves of pattern drum 15. However, since the pattern drum is turned by its own pawl 16 the equivalent of two moves, the other two moves which heretofore would have been wasted are preserved for later use. Since the double move of the pattern drum which occurs when clutching can be utilized, a single move instead of three is wasted when clutching occurs. Thus the capacity of the pattern drum and of the machine is greatly increased without material complication. Whenever rocker 24 is not riding upon a pattern chain lug, the pattern and clutch drum pawls are both inactive.

It sometimes happens that a still higher pattern chain lug such as shown at 32 in Fig. 7 is used for a special purpose or because it happens to be available. When such a lug passes under rocker 24 it would depress tail 30 of this rocker and also tail 27 of rocker 26 still more. This would not affect the rate of rotation of pattern drum 15 because its pawl is arranged to turn it at a maximum rate of two teeth per throw. However, clutch pawl 12 would also be lowered into operating position so that clutching would occur.

This might not be desired and, consequently, other means to keep clutch pawl 12 out of operation is provided. This means also serves as a safety device for preventing clutching at the wrong time when for any reason the timing of the pattern chain has been disturbed. For example, when testing the machine it is common to pull the pattern chain around by hand to reduce the time required to reach a certain point of the knitting where some difficulty may have appeared. This changes the timing of the pattern chain so that clutching would occur at the wrong time. To make this impossible under any conditions the mechanism shown in Figs. 8 and 9 is provided. This consists of an additional drum 33 rigidly attached to the same shaft as pattern drum 15. Consequently, these two drums will turn together. Drum 33 is provided with lugs 34 arranged in a corresponding manner to cams 2 and 3 on clutch drum 1. A pawl 35 is operated by cams 34 and is provided with an extension 36 which has a pin 37 underlying clutch drum pawl 12. Whenever pawl 35 is raised by a cam 34 clutch pawl 12 cannot move into operating position. Therefore, since drum 33 and pattern drum 15 must turn together, it is absolutely impossible for clutching to occur at an improper time no matter what has happened to the pattern chain and no matter what the adjustment is of rockers 24 and 26.

I claim:

1. A mechanism for a knitting machine which consists of a plurality of drums capable of independent step by step rotation, means for independently rotating one of said drums through a given angle per step, means for independently rotating another of said drums through a smaller angle per step and common means for controlling both of said rotating means so that one, both or neither of said drums is rotated as described above.

2. A mechanism for a knitting machine which consists of a plurality of drums capable of independent step by step rotation, means for rotating one of said drums through a given angle per step, means for rotating another of said drums through a smaller angle per step and common means for controlling both of said rotating means so that said last mentioned drum alone is rotated or both of said drums are rotated at said different angular step by step speeds or neither of said drums is rotated.

3. A mechanism for a knitting machine according to claim 2 in which the means for operating the common control means is an independently operated pattern chain.

4. A mechanism for a knitting machine according to claim 2 which also includes lock out means for rendering inoperative the rotating means of said first mentioned drum independently of said common control means.

5. A mechanism for a knitting machine according to claim 2 which includes lock out means for rendering inoperative the rotating means of said first mentioned drum independently of said common control means without affecting the control of said common control means upon the operating means of said first mentioned drum.

6. A mechanism for a knitting machine which consists of a clutch drum and a pattern drum, each of said drums being capable of independent step by step rotation, means for rotating said clutch drum through a given angle per step, means for rotating the pattern drum through a smaller angle per step and common means for

controlling both said clutch and pattern drums so that said pattern drum alone is rotated or both said clutch and pattern drums are rotated at said different angular step by step speeds or neither of said drums is rotated.

7. A mechanism for a knitting machine according to claim 6 in which the means for operating the common control means is an independently operated pattern chain.

8. A mechanism for a knitting machine according to claim 6 which also includes a third drum rotatable with said pattern drum and having means for rendering inoperative the clutch drum rotating means independently of said common control means.

9. A mechanism for a knitting machine which

consists of a plurality of drums capable of independent step by step rotation, means for rotating one of said drums through a given angle per step, and through a greater angle per step, means for rotating another of said drums simultaneously with the rotation of said first mentioned drum through said greater angle per step and common means for controlling both of said rotating means as above described and for preventing the rotation of both of said drums.

10. A mechanism for a knitting machine according to claim 9 which also includes lock out means for rendering inoperative the rotating means of said last mentioned drum independently of said common control means.

EUGENE ST. PIERRE.
